UNITED STATES PATENT OFFICE.

MAURUS C. RECK, OF ROCHESTER, NEW YORK, ASSIGNOR TO STERLING RANGE AND FURNACE CORPORATION, OF ROCHESTER, NEW YORK, A CORPORATION OF NEW YORK.

DESIGN FOR GAS RANGE.

Application filed May 13, 1925. Serial No. 13,429. Term of patent 7 years.

To all whom it may concern:

Be it known that I, MAURUS C. RECK, a citizen of the United States, residing at Rochester, in the county of Monroe and State of New York, have invented a new, Range, of which the following is a specification, reference being had to the accompanying drawings, forming a part thereof.

Figure 1 is a front elevation of a gas range showing my new design, and

Figure 2 is a side elevation of the same.

I claim:

The ornamental design for gas range as

MAURUS C. RECK.
